UNITED STATES PATENT OFFICE.

ARTHUR L. WALKER, OF HOOPESTON, ILLINOIS.

HOLDER FOR WHETSTONES.

1,223,127.

Specification of Letters Patent. Patented Apr. 17, 1917.

Application filed October 16, 1916. Serial No. 125,981.

To all whom it may concern:

Be it known that I, ARTHUR L. WALKER, a citizen of the United States, and a resident of Hoopeston, in the county of Vermilion and State of Illinois, have invented an Improvement in Holders for Whetstones, of which the following is a specification.

My invention is an improvement in holders for whetstones, and has for its object to provide a device of the character specified, capable of attachment to a table, wall, or other fixed support, and having means for holding the stone firmly in proper position for engagement by the blade of a knife or other tool to sharpen the said knife or tool.

In the drawings:

Figure 1 is a perspective view of the improvement in use.

Fig. 2 is a perspective view of the holder,

Fig. 3 is a partial front elevation of the holder.

In the present embodiment of the invention the improved holder, which is formed from sheet metal of suitable size, comprises a plane body portion 1, having at each end lugs 2 for engaging the ends of the stone, to hold the stone on the body, and having at each side of each end other lugs 3 and 4, respectively, for a like purpose.

The lugs 3 and 4 which are formed by bending up portions of the metal are at opposite ends of the body, and the lugs 4 which are adjacent to that end which is attached to the fixed support are bent inwardly at their upper ends to overlie the stone indicated at 5. At each side edge, and at the end adjacent to the lugs 2 and 4, the body of the holder has downwardly bent flanges 6, which are provided at their bottoms with outwardly bent portions 7, hav-

ing openings 8 or the like for the passage of a securing means to connect the holder to a fixed support, as, for instance, a table, indicated at 9.

The flanges 6 are approximately triangular in shape, being of least width adjacent to the lugs 4, and of greatest width at the opposite end, and it will be evident that when the outwardly bent portions 7 are secured to a fixed support, the holder 1 and the stone 5 thereon will be supported in inclined position, and in a convenient position for engagement by the edge of the blade to sharpen the same. The stone is placed in the holder by inserting that end which carries the paper label beneath the lugs 4, and dropping the stone in position on the body between the lugs 2 and 3. It will be understood that in practice the improved holder may be cast or otherwise formed.

I claim:

A holder of the character specified, comprising a plane body portion for receiving a stone and having means at its opposite ends for engaging the stone to hold the same on the body, said holder having at one end means for securing the holder to a fixed support with the opposite end from the said securing means inclining outwardly from the fixed support, said securing means comprising flanges extending rearwardly from the body and of greatest width at their inner end and having outwardly turned portions at their free edges provided with openings for receiving screws or the like to secure the holder in place.

ARTHUR L. WALKER.
